UNITED STATES PATENT OFFICE

2,415,731

CAR DOOR

Frank Ditchfield, Cleveland, Ohio, assignor to The Youngstown Steel Door Company, Cleveland, Ohio, a corporation of Ohio

Application November 11, 1942, Serial No. 465,233

7 Claims. (Cl. 20—22)

1

This invention relates to car doors.

It is an object of this invention to provide sliding car doors of the lift type which shall be supported at the bottom when at rest and at the top when being moved.

A further object of the invention is to provide sliding car doors of the lift type which shall embody a vertical outwardly offset portion for housing and concealing the operating bar of a lift mechanism secured to the upper margin of the doors.

It is a further object to provide sliding car doors of the lift type wherein the lift mechanism embodies an operating lever which shall also be adapted to serve as a lever for imparting initial opening and final closing movements to the doors.

It is a further object to provide headers for sliding doors of railway house cars which shall serve as a track for the doors and a reinforcement for the door openings formed in the cars.

It is a further object to provide headers for sliding doors of railway house cars which shall secure improved weather-tightness at the upper front corner of the doors.

It is a further object to provide a construction for the lower portions of sliding car doors which shall eliminate direct and reflected light and prevent snow, rain, dust, cinders, and the like from being forced upwardly into the car through the door openings.

It is a further object to provide a construction for sliding car doors which shall prevent rain, snow, dust, cinders, and the like from blowing into the car between the track and the door.

Other objects of the invention will become clear as the description thereof proceeds.

In the drawings forming part of this specification:

Fig. 1 is an elevation of a portion of a railway house car equipped with a door embodying the instant invention, parts being broken away to more clearly illustrate the invention.

Fig. 2 is a vertical section taken on line 2—2 of Fig. 1.

Fig. 3 is a vertical section taken on line 3—3 of Fig. 1.

Fig. 4 is a vertical section similar to Fig. 3 showing the door in elevated position.

Fig. 5 is a horizontal section taken on line 5—5 of Fig. 1.

Fig. 6 is a horizontal section taken on line 6—6 of Fig. 1.

Fig. 7 is a vertical section taken on line 7—7 of Fig. 1.

2

Fig. 8 is a vertical section taken on line 8—8 of Fig. 5.

Fig. 9 is a vertical section taken on line 9—9 of Fig. 5.

Fig. 10 is a horizontal section taken on line 10—10 of Fig. 1.

Fig. 11 is a horizontal section taken on line 11—11 of Fig. 1, portions of the door being broken away to more clearly show the threshold plate.

Referring to the drawings wherein a preferred embodiment of the invention is illustrated, numeral 10 designates a conventional Z-shaped side plate, the upstanding flange of which is broken away, as more clearly appears in Fig. 2 of the drawings. The side plate includes a depending flange 11 to which the upper ends of the door posts 12 and 13 are fastened in any desired manner. At their lower ends the door posts are secured to the upstanding flange 14 of an angle side sill 15. A plurality of brackets 17 are secured to the side sill reinforcing angle 16 and support a track 18 which is fastened thereto as by means of rivets 19. Wooden flooring 20 is supported on the horizontal flange of the side sill and is protected by means of a metallic threshold plate 21 hereinafter more particularly described.

A substantially J-shaped header 22 is carried by the depending flange 11 of the side plate. The header 22 embodies a vertical attaching flange 23 from the lower end of which a horizontal flange 24 projects outwardly. The flange 24 is turned upwardly to provide a flange 25. The J-shaped header by virtue of applicant's invention is extended sufficiently beyond the door posts and secured to the depending flange of the side plate and to the door posts so as to serve as a reinforcement for the car across the door opening and as a track for door lift mechanism hereinafter described. Additionally, the header serves

40 to trap foreign matter which might otherwise find its way into the car through the door opening and to this end the upstanding flange 25 of the header cooperates with a member carried by the car door to prevent any foreign matter from being blown over the flange and into the car, as hereinafter explained.

The door opening defined by the side plate, the door posts and the floor of the car is controlled by means of a door 26. This door embodies a 50 metallic panel 27 formed with a plurality of horizontal corrugations 28. Adjacent the front and rear vertical edges the metallic panel is offset outwardly from the main plane thereof as indicated at 29 and 30 and the horizontal corrugations 28 at their ends merge into the offset por-

tions of the panel. Beyond the offset portions 29 and 30 the metallic panel 27 is extended as flanges 31 and 32 which lie in a plane spaced from and parallel to the main plane of the panel.

The front vertical margin of the panel is reinforced by means of a relatively sturdy member 33. The reinforcing member 33 is formed with a flange 34 which overlies and is secured to the flange 31 of the panel. The reinforcing member 33 also embodies a web 35 extending inwardly from the flange 34, a forwardly extending flange 36 disposed substantially in the main plane of the panel and an outwardly extending flange 37 at right angles to the flange 36 and lying at the forward edge of the door. A backing plate 38 disposed in substantially the main plane of the panel is secured thereto along one margin and to the flange 36 of the reinforcing member 33 along the other margin, thereby providing a substantially box section adjacent to the forward edge of the door.

The rear vertical margin of the metallic panel 27 is reinforced by means of a member 39 provided with a flange 40 overlapping and secured to the flange 32 of the panel. From the flange 40 the reinforcing member 39 extends inwardly in the form of a web 41 flanged outwardly as indicated at 42 so as to lie substantially in the main plane of the panel. The flange 42 is flanged inwardly as indicated at 43. A reinforcing backing plate 44 is secured along one margin to the panel 27 and along the other margin to the flange 42 so as to provide a substantially box section adjacent to the rear edge of the door.

The upper margin of the metallic panel 27 is offset similar to the vertical margins of the panel as indicated at 45. The offset portion 45 is extended vertically upwardly in the form of flange 46 parallel to and spaced from the main plane of the door. The upper margin of the panel is reinforced by means of a member 47 which is substantially W-shaped in section. The reinforcing member 47 embodies a depending flange 48 overlapping and secured to the upstanding flange 46 of the panel, an inwardly extending web 49, an upstanding flange 50, and an inwardly directed flange 51. A reinforcing backing plate 52 is secured to the panel 27 substantially in the main plane thereof and to the flange 50 of the reinforcing member 47 and cooperates therewith and with the offset portion and upstanding flange 46 of the panel to form substantially a box section. It will be observed from Fig. 1 of the drawings that the vertical backing plates 38 and 44 and the upper horizontal backing plate 52 terminate short of the upper corners of the door. The reason for this will hereinafter appear.

The lower margin of the door is formed with a flange 53 immediately below the lowermost horizontal corrugation 28. This corrugation is spanned by means of a reinforcing backing plate 54 secured along the upper margin substantially in the main plane of the panel. The flange 53 of the panel and the lowermost marginal portion of the backing plate are secured as by means of rivets 55 to one flange 56 of a T-shaped reinforcing member 57, the flange 56, as more clearly appears in Fig. 3, being disposed between the flange 53 of the panel and the backing plate. The T-shaped reinforcing member 57 also embodies a flange 58 which lies behind the track 18 and an outwardly extending stem 59 which is adapted to seat upon and frictionally support the door 26 when it is not being moved in opening or closing direction. As more clearly appears in Figs. 1 and

5 of the drawings, the lower end of the panel reinforcing member 33 is flattened, as indicated at 60, so that it can be shaped to the contour of the underside of the lowermost corrugation 28 and the flange 53 of the panel. A similar construction is employed for the lower portion of the rear vertical reinforcing member 39, as indicated at 61.

As indicated above, the door is frictionally supported upon the lower track 18 when it is at rest. Lift mechanism is provided for the purpose of elevating the door above the track 18 and supporting it upon anti-friction means to permit movement of the door in opening and closing directions. This mechanism is secured to the upper portion of the door and embodies a metallic plate member 62 secured to the upper front corner of the door between the vertical and horizontal backing plates 38 and 52. The plate member 62 thereby serves in effect as a continuation of these backing plates and by its securement to the metallic panel substantially in the main plane thereof and to the flange 36 of the vertical reinforcing member 33 and the flange 50 of the horizontal reinforcing member 44 provides extensions of the horizontal and vertical box sections hereinabove described. A substantially channel shaped housing member 63 is secured to the inner face of the plate member 62. The channel member 63 is formed with a web 64 spaced inwardly from the plate member 62, legs 65 and 66 directed toward the plate member and attaching flanges 67 and 68 by means of which the channel shaped housing member 63 is fastened to the plate member 62. A roller retainer 69 is disposed within the channel shaped housing member 63 and is formed with inner and outer trunnions 70 and 71 journaled respectively in the web 64 of the housing member 63 and in the plate member 62. The retainer 69 carries a roller 72 the axis of rotation of which is offset from the axis of the trunnions, as more clearly shown in Fig. 5 of the drawings. The roller retainer 69 is formed with an inwardly extending lug 73 for a reason which will hereinafter appear.

A similar construction is provided at the upper rear corner of the door and it is believed that the description of the construction at the upper front corner of the door will suffice for the construction at the upper rear corner of the door. A bar 74 mounted upon the lugs 73 of the front and rear roller retainers serves to connect these retainers for simultaneous operation.

The outer trunnions 71 of the front and rear roller retainers are extended outwardly so as to lie within the upper horizontal box section of the door. The outer ends of the trunnions 71 are journaled in bearing plates 75 fastened to the inner face of the upstanding flange 46 of the panel. A forked link 76 is fixedly secured to the trunnion 71 at the upper front corner of the door and projects from the trunnion so that its forward end lies within the vertical box section adjacent to the front edge of the door. A pin 77 extends between the forks of the link 76 and is utilized to pivotally fasten the upper end of a vertical actuating bar 78 to the link. The actuating bar 78 extends downwardly within the vertical box section adjacent the front edge of the door so as to be housed and concealed thereby. The lower end of the actuating bar 78 is pivotally connected to a link 79 by means of a pin 80 extending through the forks of the link. The link 79 is fixedly secured to a shaft 81, the inner end of which is journaled within a bear-

ing plate 82 secured to the panel substantially within the main plane thereof and to the flange 36 of the front vertical reinforcing member 33. An intermediate portion of the shaft 81 is journaled in a substantially Z-shaped bearing plate 83, one flange 84 of which is secured between an offset portion 85 of the metallic panel and the bearing plate 82 as more clearly shown in Fig. 6 of the drawings. The web 86 of the bearing plate extends outwardly and the flange 87 thereof extends forwardly in abutting relationship with the flange 31 of the panel and provides the bearing for the intermediate portion of the shaft 81. This shaft projects outwardly beyond the outer face of the door and an operating lever 88 is fastened to the outwardly projecting portion. It will be apparent in view of the foregoing description that the lever is the only part of the lift mechanism which is visible from the outside of the door.

It will be clear from the foregoing that when at rest the weight of the door is carried by the lower track 18 thereby relieving the upper track 22. The latter supports the weight of the door only when it is being moved. To secure movement of the door upon the rollers 72 the operating lever 88 is swung counterclockwise. The link 79 to which the lever is fastened thereupon exerts a downward force upon the actuating bar 78 which in turn exerts a similar force upon the upper link 76. Since this link is fixed upon the outer trunnion of the roller retainer 69, rotation is imparted to said retainer which by the agency of the connecting bar 74 is transmitted to the roller retainer at the upper rear corner of the door. This rotation of the roller retainer forces the rollers against the track 22 and the resulting reaction through the trunnions of the roller retainers exerts an upward force upon the door so as to raise it above the lower track 18 and support it for movement upon the rollers 72. When the lever is released the door will automatically gravitate to its lowermost position at which time the weight of the door will be transferred from the upper track to the lower track 18.

In the lowering movement of the door the lever swings in clockwise direction. The motion of the operating lever of the lift mechanism is utilized to impart opening and closing movements to the door. To this end an arm 89 is pivotally secured to the car adjacent to the forward edge of the door opening by means of a bracket 90 fastened to the car. Both the operating lever and the closing arm swing in a plane parallel to the car. The arm 89 is provided with a recess 91 adapted to receive a lug 92 formed on the upper end of the operating lever 88. When the door is in closed and lowered position and it is desired to open the door, swinging movement of the lever 88 counterclockwise will raise the door and also cause the lug 92 to bear against the recess 91 in the closing arm, thereby imparting a thrust to the door to move it in opening direction. As illustrated in Fig. 1, it is preferred that clearance be provided between the lug and the recess in the closing arm so that the door will be supported upon the rollers prior to the engagement between the lug and the recess. Opening thrust upon the door is thereby insured when the door is on the rollers.

The operating lever swings in clockwise direction during lowering movement of the door. When the lever is operated clockwise and the lug 92 is in engagement with the recess 91 of

the closing arm a thrust is exerted upon the door which will force the door to its closed position. It will be evident that until the operating lever assumes the position illustrated in Fig. 1 the door will be supported upon the rollers so that the force exerted upon the door to close it will be effective in the main when the door is still supported upon the rollers. The force required to close the door will, therefore, be reduced.

With reference to Figs. 2 and 5 of the drawings, it will be observed that the inwardly extending flange 51 of the door reinforcing member 47 lies vertically above the header-track member 22 so as to cooperate therewith in the securing of a weathertight door. In Fig. 6 of the drawings a conventional stop 93 is illustrated. This stop embodies a substantially channel shaped portion 94 which receives the front vertical portion of the door when it is closed. A flange 95 extends inwardly from the channel shaped portion 94 and terminates in an attaching flange 96 which is disposed parallel to and is secured to the front door post 12. Prior to applicant's invention the front door stop 93 continued upwardly to the door retaining bar 97, which, as illustrated in Fig. 2 of the drawings, is Z-shaped in section and secured to the depending flange 11 of the side plate 10.

Referring to Figs. 2, 4, and 6 of the drawings, it will be apparent that the header in the prior constructions could not extend forwardly beyond the flange 95 of the front stop and it is customary to terminate the header at this point. Moreover, in the prior constructions in order to permit the door to assume its fully closed position, it is necessary to cope the inwardly extending flange of the top door reinforcing members adjacent to the front vertical edges of the doors so that these flanges would not strike against the inwardly extending flange 95 of the front stop and prevent the doors from being fully closed. This coping of the inwardly extending flanges of the door reinforcing members, however, provides a substantially direct opening between the upper front corner of the door and the front stop, permitting dust, cinders, rain, snow and the like to readily find their way into the car through the door opening.

The instant invention eliminates this opening and substantially improves the weathertightness of the upper front corner of the door. As more clearly disclosed in Figs. 1, 2, 5 and 8 of the drawings, the front door stop 93 is terminated below and adjacent to the header-track 22. The header-track 22, consequently, is extended forwardly beyond the door stop and the flange 51 of the door reinforcing member 47 is permitted to extend continuously substantially to the front vertical edge of the door. To close the opening above the header provided by this construction a plate member 98 is utilized. This member is shown more clearly in Fig. 8 of the drawings and embodies an outwardly and rearwardly directed flange 99 which is similar to and disposed upon a corresponding flange of the channel portion 94 of the front stop. The plate member 98 is also provided with an inwardly extending flange 100 which is disposed upon a corresponding flange 75 of the channel shaped portion 94 of the front stop and extends inwardly to the attaching flange of the header-track to which it is secured as by means of welding. The inwardly extending flange 100 is coped, as more clearly shown in Fig. 75 of the drawings, to clear the upstanding flange

25 of the header-track. At its upper portion the plate member 98 extends to the depending flange 101 of the retaining bar 97. Inwardly of the depending flange 101 the inwardly extending flange 100 follows the inner contour of the retaining bar 97 and extends continuously downwardly therefrom to the outwardly extending flange 24 of the header track.

It will be apparent from the foregoing construction that the inwardly extending flange 100 serves as an abutment flange for the door above the door stop 93 and that the inwardly extending flange 51 of the door reinforcing member 47 extends continuously to flange 100 which it is adapted to abut when the door is closed. It is apparent, therefore, that the opening provided by the cope of the inwardly extending flange hereinabove described is eliminated and that a materially improved weathertight construction is afforded for the upper corner of the door.

Additional weather protection for the upper portion of the door is provided by the instant invention. This takes the form of a Z-shaped member fastened to the door between the front and rear channel shaped housing members of the lift mechanism. This Z-shaped member 102 is more clearly illustrated in Figs. 5 and 9 of the drawings and embodies an upstanding attaching flange 103, an inwardly extending web 104 which extends across the upstanding flange 25 of the header-track member 22 and a depending flange 105 which extends downwardly behind flange 25 of the header-track. The attaching flange 103 and the web 104 are coped at the ends of the Z-shaped member, as indicated at 106, to clear the adjacent attaching flanges of the channel shaped housing members 63. The Z-shaped member 102 accordingly cooperates with the upstanding flange 25 of the header-track 22 to prevent any matter which may lodge in the trough of the header-track from being blown over the flange 25 and into the car through the door opening.

The weathertightness of the upper portion of the door is further enhanced by means of a baffle plate 107 which is secured to the rear channel shaped housing member 63 as by means of welding and which extends upwardly therefrom to the inwardly extending flange 51 of the door reinforcing member 47. The baffle plate 107 is preferably welded to the inwardly extending flange 51. The employment of a baffle plate, such as plate 107, materially reduces the size of the opening at the upper rear corner of the door and serves to baffle any foreign matter which otherwise might be blown behind the door.

The weathertightness of the door at the bottom thereof is also substantially improved. The T-shaped reinforcing member secured to the lower margin of the door and the association thereof with the bottom supporting track 18 effectively prevents foreign matter from being blown into the car from the outside of the door. The depending flange 58 of the T-shaped reinforcing member 57 is also utilized in cooperation with the threshold plate 21 to further preclude entry of foreign matter into the car and to prevent the entry of direct and reflected light. As clearly appears in Fig. 3 of the drawings, the threshold plate lies flatwise upon the floor 28 of the car and is conventionally fastened thereto and to the side sill and side sill reinforcement by bolts (not shown). The threshold plate projects outwardly beyond the side sill 15 and the projecting portion is supported by means of an angle

member 108 which is fastened to the vertical leg of the side sill as by means of rivets 109. Beyond the supporting angle 108 and between the door posts the threshold plate is flanged downwardly as shown at 110. Angle clips 111 are secured to the flange 110 as by means of welding and are disposed in substantial abutment with the underside of the supporting angle to retain the threshold plate in position. The vertical flange 110 of the threshold plate terminates in an outwardly projecting flange 112 or lip which extends across and beyond flange 58 of the T-shaped reinforcing member 57 and lies adjacent to the lower edge thereof. This relationship between the flange 58 and the outwardly projecting flange 112 of the threshold plate effectively prevents direct and reflected light from entering the car and provides a baffle preventing foreign matter from being blown upwardly into the car between the door and the depending vertical flange 110 of the threshold plate. While the depending flange 110 lies within the door opening the effectiveness of the outwardly projecting flange 112 is maintained both forwardly and rearwardly of the door opening by the extensions 113 and 114.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. An outside sliding lift door for railway house cars comprising a metallic panel offset outwardly from the main plane thereof adjacent to and along both the front vertical and upper horizontal edges of said door, said offset portions communicating with each other, lift mechanism secured to the upper horizontal margin of said door inwardly of the main plane of said panel and below the top of said door, said mechanism lying between the main plane of said panel and the adjacent wall of said car when said door is mounted on said car, a vertical actuating member within said vertical offset, means within said horizontal offset connecting said lift mechanism and said actuating member, an operating lever for said lift mechanism on the outside of said door, and means within said vertical offset connecting said lever and said actuating member.

2. In a railway house car, in combination, an outside sliding lift door having a metallic panel, a track secured to said car adjacent to the upper portion of said door, lift mechanism embodying rollers secured to the upper portion of said door, a vertical actuating bar, means connecting said lift mechanism and said bar, an operating lever for said lift mechanism, means pivotally mounting said lever for swinging movement in a plane parallel to and on the outside of said door, a member connecting said latter means and said bar, said lever being operable to actuate said bar to lift and support said door upon said rollers for movement along said track, and means carried by said car adapted to be engaged by said lever to open and close said door.

3. In a railway house car, in combination, an outside sliding lift door, a track secured to said car adjacent to the upper portion of said door, lift mechanism embodying rolling means secured to the upper portion of said door, a vertical bar connected to said lift mechanism, an operating lever for said lift mechanism pivotally mounted

upon said door for movement in a plane parallel to the door, means operatively connecting said lever and said bar, said lever being operable in a plane parallel to said door to actuate said bar to lift and support said door upon said rolling means for movement along said track, and means carried by said car adapted to be engaged by said lever to open and close said door, said lever moving in one direction in said plane to lift said door and to open said door and in the opposite direction in said plane to lower said door and to close said door.

4. In a railway house car, in combination, a sliding lift door, a track secured to said car, lift mechanism embodying rolling means secured to said door, an operating lever for said lift mechanism swingable in a plane parallel to the door, said lever being operable in a plane parallel to said door to actuate said lift mechanism to support said door upon said rolling means for movement along said track, and means carried by said car adapted to be engaged by said lever to open and close said door, said lever moving in one direction in said plane to lift said door and to open said door and in the opposite direction in said plane to lower said door and to close said door.

5. In a railway house car having a door opening, a track secured to said car adjacent to the upper portion of said door opening, a sliding lift door, lift mechanism embodying rollers secured to the inner face of said door adjacent to the upper corners thereof, housing members for said rollers secured to said door, said housing members terminating below the upper edge of said door, and a baffle member secured to and extending upwardly from the housing member at the upper rear corner of said door substantially to the upper edge of said door, said baffle member cooperating with said rear housing member to baffle the flow of foreign matter between said door and track into said door opening, said rollers being adapted to roll upon said track during opening and closing movements of said door.

6. In a railway house car having a door opening, a track secured to said car adjacent to the upper portion of said door opening, a sliding lift door, an inwardly extending reinforcing flange secured to the upper margin of said door, lift mechanism embodying rollers secured to the inner face of said door adjacent to the upper corners thereof, housing members for said rollers secured to said door, said housing members terminating below said door reinforcing flange, and a baffle member secured to the housing member 65

at the upper rear corner of said door, said baffle member extending upwardly to said door reinforcing flange and cooperating with said rear housing member to baffle the flow of foreign matter between said door and track into said door opening, said rollers being adapted to roll upon said track during opening and closing movements of said door.

7. In a railway house car having a door opening, a track secured to said car adjacent to the upper portion of said door opening, said track comprising a vertical attaching flange, an outwardly extending flange and an upwardly extending flange spaced from said attaching flange, 15 a sliding lift door, an inwardly extending reinforcing flange secured to the upper margin of said door, lift mechanism embodying rollers secured to the inner face of said door adjacent to the upper corners thereof, housing members for said rollers secured to said door, said housing members terminating below said door reinforcing flange, 20 a baffle member secured to the housing member at the upper rear corner of said door, said baffle member extending upwardly from said housing member to said door reinforcing flange and cooperating with said rear housing member to baffle the flow of foreign matter between said door and track into said door opening, and a sealing strip secured to said door and extending 25 substantially between said housing members, said sealing strip having a downwardly extending flange overlapping the inner face of said upwardly extending track flange, said rollers being adapted to roll upon said outwardly extending track flange during opening and closing movements of said door.

FRANK DITCHFIELD.
